UNITED STATES PATENT OFFICE.

JOHN KORZINEK, OF PASSAIC, NEW JERSEY, ASSIGNOR TO THE HOBBS WALL PAPER COMPANY, A CORPORATION OF NEW JERSEY.

DESIGN FOR WALL-PAPER.

49,650.

Specification for Design.

Patented Sept. 12, 1916.

Application filed March 25, 1916. Serial No. 86,821. Term of patent 3½ years.

To all whom it may concern:

Be it known that I, JOHN KORZINEK, a citizen of the United States, residing in the city of Passaic and State of New Jersey, have invented a new, original, and ornamental Design to be Applied to Wall-Paper; and I hereby declare the following to be a description of the same in such terms as will enable any person skilled in the art to which it appertains to make and use the same, reference being had to the accompanying drawing.

The figure of the drawing shows my design.

The design is for superficial ornamenta-

tion by printing it on wall paper to be used in mural decorations. It is intended to be repeated or matched out on all sides thereof indefinitely as is usual in wall papers.

The design represents leaves, stems, and vines together with irregular configurations forming vertical strips, *a, a*.

What I claim is:

The ornamental design to be applied to wall paper as shown and described.

JOHN KORZINEK.
